UNITED STATES PATENT OFFICE

JAMES M. HARRISON, OF CLEVELAND, OHIO

APPARATUS FOR THE HEATING OF OVENS AND THE LIKE

Application filed December 29, 1926. Serial No. 157,660.

This invention relates to an apparatus for and process of supplying heated fluids to ovens or kilns such as are used for the drying and baking of enameled products, japsans, 5 paints, or other coatings, drying and baking foundry cores, etc.

It is the general purpose and object of the invention to provide an improved process and apparatus for accomplishing this purpose, the invention being adapted particularly to systems wherein the mixture of products of combustion and air is supplied to such ovens or furnaces by means of a fan; a further object of the invention is to enable the 15 purpose to be accomplished with a saving in expense as compared with that involved in existing practices.

The usual manner of applying products of combustion to ovens of the type referred to 20 by means of an induced-draft fan is substantially as follows:—Oil is burned within a combustion chamber having an incandescent refractory lining or checker work therein, the oil being burned in such manner as to 25 maintain such refractory material at incandescence. This incandescent condition enables the oil to be burned completely and also enables the combustible mixture of oil and air to be ignited by such incandescent lining 30 or checker work, should a temporary interruption occur in the supply of oil and air to the chamber. As a necessary result of this mode of combustion, the gases leaving the combustion chamber are at a very high tem- 35 perature. In order to supply the drying oven with air and gas at the desired temperature, a cold air branch connection is made outside the combustion chamber to the duct leading to the induced-draft fan. By pro- 40 viding such draft in this duct, the products of combustion leaving the combustion chamber at comparatively high temperatures as, for instance, 1000° F. are diluted to bring the temperature of the mixture entering the fan 45 casing to a considerably lower temperature, as required, say approximately 600° F.

In the operation of my apparatus and in the practice of my process, a burner is em- 50 ployed which serves to atomize the oil and enable the same to be burned in the combustion

chamber without the aid of incandescent lin- 55 ings, baffles or checker work. The tempera- ture of the gases leaving the combustion chamber need not exceed 900° F.

Furthermore, instead of introducing cold 60 air directly into the duct connecting the induced-draft fan with the combustion chamber, the air is drawn deliberately through the combustion chamber, whereby the tempera- 65 ture of the air is raised by contact with the flame and the temperature of the products of combustion is lowered by direct mingling of the air and products of combustion within the combustion chamber, the temperature of the air being raised to the proper extent by con- 70 tacting with the flame and by contacting and intermingling with the products of combustion, as well as by convection from hot sur- 75 faces and by radiation from the flame. The mixture is conducted directly from the com- bustion chamber to the fan and is delivered thence into the oven.

Referring to the drawings, which illus- 80 trate the present preferred form of appara- tus by which the process is realized, Fig. 1 75 represents a side elevation of the heater, oven and fan; Fig. 2 is a central vertical sectional view through the heater; Fig. 3 is a sectional view corresponding substantially to the line 3—3 of Fig. 2, certain parts being broken away; Fig. 4 is a front elevation of the heater; and Fig. 5 a transverse vertical sectional view through the heater.

Describing the various parts by reference 85 characters, A denotes the heating furnace generally, B the oven, and C the induced-draft fan, the central portion of which re- ceives the heated air and products of combus- 90 tion discharged from the furnace through the duct D, the fan delivering such mixture through the duct E into the oven B.

The heater or furnace is provided with 95 metal sides 1 and a metal top 2, the top being shown as strengthened by angle irons 3 hav- ing their vertical flanges placed back to back and suitably united. The metal top 2 extends beyond the sides 1, and the angles between the top and sides are strengthened by the angle irons 4. Above the bottom of each side 1 and fastened thereto is a Z bar 5, the bars 100

and the sides 1 supporting a lining 6 of insulating material.

7 denotes the metal front wall and 8 the metal rear wall of the furnace, the front wall being shown as strengthened by vertical angle irons 7^a and 7^b placed back to back and the rear wall being shown as strengthened in like manner by vertical angle irons 8^a and 8^b also placed back to back. The top of the front wall 7 is also provided with transverse angle irons 7^c and 7^d, the former angle iron assisting to support the metal top 2. The rear wall 8 is provided with an angle iron 8^c near the top and assisting to support the top plate 2.

Secured above the bottom of the rear wall 8 and projecting inwardly therefrom is the angle iron 8^d which assists in supporting the lining 9 of insulating material, there being a similar lining within the front wall 7. The walls 1, 2, 7 and 8 and the lining constitute an outer shell for the furnace. Within the linings 6 and spaced inwardly from the walls 1 are the metal walls 10, said walls running the full length of the heater and having their outer ends secured between flanges of the angle irons 7^a, 7^b and 8^a, 8^b. Each wall 10 is provided at its bottom with an angle iron 10^a forming part of the footing for the furnace. Above the angle irons 10^a are angle irons 10^b which support cross bars 11, these cross bars in turn supporting the refractory slabs 12 constituting the bottom of the combustion chamber. The angle irons 10^b also support the refractory slabs 13 constituting the side walls of the combustion chamber, the said side-wall slabs being also supported by the metal sides 10. The slabs 13 are provided with suitable brackets 14 which support slabs 15 resting thereon and extending transversely of the combustion chamber at the rear thereof and engaging with their ends the slabs 13. The slabs 13 are also provided with brackets 13^a which are adapted to support the upwardly arched refractory slabs 16 extending transversely of the combustion chamber and constituting a baffle located below the roof of the casing.

Extending across the top of the combustion chamber, above the arches 16, are the refractory roof slabs 17, said slabs being supported on top of the side slabs 18, which constitute an extension of the slabs 13. Within the insulating walls 9 are the rear wall 19 and front wall 20, respectively, of the combustion chamber, the said walls also being of refractory material, preferably slabs of the type employed for the other walls of the said chamber.

Extending from the rear of the combustion chamber is the connection 21 from which the duct D extends to the fan C. This connection projects inwardly through the walls 9 and 19 and communicates with the rear of the chamber G above the combustion cham-

ber proper indicated at F, the chamber F being separated from the outlet by a transverse wall 22 of refractory material resting upon one of the slabs 15 and extending upwardly to the rear arch 16.

Secured to and depending from each of the angle irons 10^b and projecting inwardly therefrom is a Z bar 23, the bottom flanges of the bars projecting toward each other and the inner edge of each such flange being approximately in the plane of the side edge of the bottom wall 12 of the combustion chamber.

Between each lateral edge of the bottom 75 12 and the side wall 13 adjacent thereto is a slot 24.

The front of the heater is provided with a burner plate 27 the said plate having a pair of frusto-conical sleeves 27^a projecting inwardly therefrom, each extending into the outer end of a burner tile 28. Projecting into each of the sleeves 27^a is a burner 29 of the atomizing type, each such burner having an oil supply 30 and a steam or air supply 31.

It will be noted that a wide port 32 is provided at the front of the heater and along the sides thereof below the burner plate, for the supply of air beneath the bottom tiles 12 of the combustion chamber. Below the roof 17 of the combustion chamber the front wall 95 is provided with a peep hole 33.

With the parts constructed and arranged as described, the burners will be operated in the usual manner, delivering a combustible mixture of air and combustible fluid into the combustion chamber, the mixture being ignited and burned in the usual manner. Owing to the type of burners employed, it will be unnecessary to employ in my heater, checker work, baffles, or other arrangement 100 of refractory material intended to be heated to incandescence; and it will be unnecessary to heat the combustion chamber to any such incandescent temperature in order to secure the proper functioning of the furnace for the purposes of my invention. Air admitted through the port 32 will be distributed by the Z bars 23 and the slots 24 into the bottom of the combustion chamber, at each side 105 thereof.

As the air rises, it comes into contact with the flames of the burners and is heated thereby by convection and by the products of combustion, with which it 110 mingles. An intimate mixture of the air and products is formed within the chambers F and G and is delivered from the latter chamber through the outlet connection 21 into the duct D.

By the operation of the apparatus described herein, air for diluting the products 125 of combustion is supplied directly to the combustion chamber; is heated by convection and by the flames from the burners therein; is mingled therein with the products of combustion; and the mixture thus formed is 130

taken directly from the chamber and delivered by the induced-draft fan into the oven B. Through the operation of the apparatus and by reason of the process accomplished thereby, I am enabled to produce, in a very efficient and economical manner, a heated fluid adapted for use in ovens for enameling and other purposes, and am able to accomplish this result without the necessity for any special type of burner or for a special and expensive type of combustion chamber.

Having thus described my invention, what I claim is:—

1. A furnace of the character described comprising an outer metallic shell, a lining of insulating material within said shell, refractory material within the said shell arranged to form a combustion chamber, there being metal side walls for said refractory material and interposed between the same and the side insulating walls, the said combustion chamber being provided with transverse arches below the top thereof and supported from the side walls, there being an outlet from the combustion chamber at the rear end thereof and communicating with the space between said arches and the top of the combustion chamber.

2. A furnace of the character described comprising a surrounding casing, a combustion chamber within said casing, the said combustion chamber comprising side, top and bottom walls of refractory material, the side walls being provided with brackets below the top thereof, longitudinally-spaced arched slabs supported by said brackets and forming with the top a chamber communicating directly with the combustion chamber throughout the major portion of the length of the latter, a refractory slab extending across the rear of the combustion chamber below the arched slabs, a transverse slab forming with such refractory slab and one of the arched slabs a barrier between the combustion chamber and the space thereabove, there being an outlet for gases of combustion at the rear of the combustion chamber and communicating with said chamber above said barrier.

3. A furnace of the character described comprising a surrounding casing, a combustion chamber within said casing, the said combustion chamber comprising side, top and bottom walls of refractory material, longitudinally spaced arched slabs extending across the combustion chamber and forming with the top a chamber communicating directly with the combustion chamber throughout the major portion of the length of the latter, refractory material extending across the rear of the combustion chamber below the arched slabs, a transverse slab forming with such refractory material and one of the arched slabs a barrier between the

combustion chamber and the space thereabove, there being an outlet for gases of combustion at the rear of the combustion chamber and communicating with said chamber above said barrier.

4. A furnace of the character described comprising a surrounding casing, a combustion chamber within said casing, the said combustion chamber comprising side, top and bottom walls of refractory material, the side walls being provided with brackets below the top thereof, longitudinally-spaced arched slabs supported by said brackets and forming with the top a chamber communicating directly with the combustion chamber throughout the major portion of the length of the latter, a refractory slab extending across the rear of the combustion chamber below the arched slabs, a transverse slab forming with such refractory slab and one of the arched slabs a barrier between the combustion chamber and the space thereabove, there being an outlet for gases of combustion at the rear of the combustion chamber and communicating with said chamber above said barrier, said combustion chamber being provided with a slot in the bottom thereof and adjacent each side wall, each slot extending substantially the full length of the combustion chamber.

5. A furnace of the character described comprising an outer shell, a lining of insulating material within said shell, refractory material within the said shell arranged to form a combustion chamber, there being metal side walls for said refractory material interposed between the same and the side insulating walls, the said combustion chamber being provided with transverse arches below the top thereof and supported from the side walls, there being an outlet from the combustion chamber communicating with the space between said arches and the top of the combustion chamber.

6. A furnace for a system or apparatus of the character specified consisting of a combustion chamber, one or more burners for delivering a mixture of fluid fuel and air into the said combustion chamber, the said combustion chamber having walls of refractory material and provided with slots in the bottom wall thereof extending substantially the full length of the combustion chamber and arranged one on each side thereof whereby to permit the upward flow of air to the said combustion chamber and into the flame and products of combustion.

7. A furnace of the character described comprising a surrounding casing, a lining of insulating material for said casing, a partition arranged within said casing and dividing the same into an upper compartment and a lower compartment, said partition having slots therein connecting said upper and lower compartments, the bottom of said casing hav-

ing one or more slots therein extending substantially the full length thereof for the upward flow of air into the lower compartment, an outlet leading from the upper compartment and one or more burners for delivering a mixture of fluid fuel and air into the lower compartment, the said casing being provided with a lining of refractory material.

8. A furnace of the character described comprising a surrounding casing, refractory material within said casing and arranged to form a combustion chamber, a partition arranged within said combustion chamber and dividing the same into upper and lower compartments, said partition having one or more slots therein connecting said upper and lower compartments, the bottom of said combustion chamber having one or more slots extending substantially the full length of the combustion chamber for the upward flow of air to the said combustion chamber and into the flame and products of combustion, an outlet leading from said upper compartment and one or more burners for delivering a mixture of fluid fuel and air into the said combustion chamber.

In testimony whereof, I hereunto affix my signature.

JAMES M. HARRISON
